(57) **CLAIM**

The ornamental design for an electrical charging port, as shown and described.

DESCRIPTION

FIG. 1 is a perspective view of an electrical charging port showing our new design, with the cover off.

FIG. 2 is a front view thereof.

FIG. 3 is a rear view thereof.

FIG. 4 is a left side elevational view thereof.

FIG. 5 is a right side elevational view thereof.

FIG. 6 is a top view thereof.

FIG. 7 is a bottom view thereof; and,

FIG. 8 is a perspective view thereof, with the cover on. The ornamental design which is claimed is shown in solid lines in the drawings. In the drawings, the broken lines are for the purpose of illustrating portions of the electrical charging port that form no part of the claimed design.
